CARBURETOR

Scott F. Hunt, Meriden, Conn., assignor to Niles-Bement-Pond Company, West Hartford, Conn., a corporation of New Jersey

Original application June 17, 1943, Serial No. 491,096, now Patent No. 2,442,046, dated May 25, 1948. Divided and this application November 20, 1947, Serial No. 787,101

18 Claims. (Cl. 261—34)

1 This is a division of my co-pending application, Serial No. 491,096, filed June 17, 1943, entitled Carburetors, and matured into Patent No. 2,442,046, issued May 25, 1948.

This invention relates to carburetors for internal combustion engines, and particularly to means for operating such carburetors so as to provide improved acceleration characteristics of the engine.

It has previously been proposed to provide, in a carburetor for an internal combustion engine, a device responsive to the pressure in the air induction system at a point downstream from the throttle, and effective upon an increase in such pressure, such as accompanies a sudden opening movement of the throttles, to inject into the air stream an additional supply of fuel so as to rapidly accelerate the engine.

It has been found that with devices of the type described, the additional supply of fuel provided is not always sufficient to complete the acceleration of the engine to a speed corresponding to the new throttle position. Such a device provides a momentary additional supply of fuel for the engine, but it has been found that this additional supply of fuel may be completely dissipated before the acceleration of the engine is completed.

It is therefore an object of the present invention to provide improved means for supplying additional fuel to an internal combustion engine during acceleration of the engine.

A further object of the invention is to provide an improved fuel supply system for an internal combustion engine wherein a first device is used to give an increased fuel supply immediately in response to acceleration of the engine, and a second device is used to provide another additional fuel supply after a time delay following the initiation of a period of acceleration.

A further object of my invention is to provide a device of the type described wherein the valve which normally controls the fuel supply to the engine is utilized during periods of acceleration to supply an additional amount of fuel to the engine.

Another object of the present invention is to provide an improved carburetor of the type in which the fuel flow controlling valve is operated by fuel pressure controlled by a pilot valve, in which means are provided to increase the pressure on the fuel flow controlling valve in response to acceleration of the engine on which the carburetor is used.

Another object of the present invention is to provide, in a carburetor of the type described, a

pressure operated device which responds to an increase in the intake manifold pressure to supply an additional amount of fuel to the engine, and which operates cumulatively in response to the increased fuel supply to further increase the supply of fuel.

A further object of the invention is to provide an improved pressure controlling device which is balanced against the controlled pressure so that upon the application of a force to the pressure controlling device, it operates throughout its range of movement, without being retarded by changes in the controlled pressure.

A further object of the invention is to provide, in a carburetor having a throttle controlling the flow of air, means responsive to the pressure downstream from the throttle for supplying additional fuel to the engine upon acceleration thereof, and means for balancing the pressure responsive means against changes in atmospheric pressure.

A further object of the present invention is to provide improved means for supplying additional fuel to an internal combustion engine upon acceleration, comprising a valve connected in parallel with a fuel regulating valve and controlled as an incident to acceleration of the engine. A still further object is to provide, in such an arrangement, a fuel reservoir having an outlet controlled by an acceleration responsive valve and an acceleration responsive pump for emptying the reservoir. A still further object is to provide such an arrangement in which the valve is maintained open for a period of time longer than that required for the pump to empty the reservoir.

Other objects and advantages of the present invention will become apparent from a consideration of the appended specification, claims and drawing which illustrates, somewhat diagrammatically, an aircraft carburetor embodying certain principles of my invention.

There is shown in the drawing a carburetor body portion 1 including an air passage generally indicated at 2. Air enters the passage at an inlet 3, flows thru a Venturi restriction 4, past a throttle 5 and a discharge nozzle 6 to an outlet 7.

A second air passage connects the air inlet 3 and the throat of venturi 4. This second air passage may be traced from the inlet 3 thru a plurality of impact tubes 8, a vent ring 9, a conduit 10, an expandible chamber 11, a restriction 12, an expandible chamber 13, a conduit 14, a valve chamber 15, and a conduit 16 to the throat

of venturi 4. As it enters the chamber 15 from conduit 14, the air flowing thru this second passage flows past a valve 17 controlled by a bellows 18, which is mounted in the chamber 15. The purpose of the bellows 18 is to compensate the air flow thru this second passage in accordance with variations in density of the flowing air, as described in connection with bellows 135 of my aforementioned Patent No. 2,442,046.

The chambers 11 and 13 are part of a metering unit 19, which includes a casing 20 separated by a pair of transverse diaphragms 21 and 22 into expandable chambers 11, 13 and 23. A motion transmitting member 24 is attached to the center of diaphragm 21, and acts against the center of diaphragm 22. The center of diaphragm 22 is thereby moved to close or open a valve port 25 in the housing 20. A spring 26 biases the member 24 toward a position wherein the valve port 25 is closed by the diaphragm 22.

The fuel supply to the carburetor passes from a pump or other source of fuel under pressure (not shown) thru a conduit 27, a fuel regulator unit 28, a conduit 29, a mixture control unit 30, a jet system 31, a conduit 32, a pressure regulator 33, and a conduit 34 to the discharge nozzle 6.

The fuel regulator unit 28 comprises a housing 35 separated by a diaphragm 36 into a pair of expandable chambers 37 and 38. The diaphragm 36 carries at its center a balanced valve 39, which controls the flow of fuel from the conduit 27 thru the chamber 38 to the conduit 29. A compression spring 40 biases the valve 39 for movement toward open position.

The position of valve 39 is determined by the difference between pressures in the chambers 37 and 38 and by the force exerted by the spring 40. The chambers 37 and 38 are connected by a restriction 41.

A portion of fuel entering the chamber 38 flows thru the restriction 41, chamber 37, a conduit 42, past a valve 43, thru a conduit 44, a check valve 45, a conduit 46, expandable chamber 23 of the metering unit 19, and a conduit 47 to an opening 48 in the wall of air passage 2.

The check valve 45 permits a flow thru the conduit just traced in a direction from the fuel regulator unit 28 to the pressure meter 19.

The mixture control unit 30 includes a disc valve 49 fixed on a shaft 50. The shaft 50 may be manually rotated, by means not shown, so that the disc 49 controls the flow of fuel from the conduit 29 to a pair of conduits 51 and 52 leading to the jet system 31. When the shaft 50 is in a position so that fuel can flow only thru the conduit 52 and not thru conduit 51, the mixture control is said to be in the "lean" position. When the disc valve 49 is in a position such that fuel can flow thru both conduits 51 and 52, the mixture control is said to be in the "rich" position.

The conduit 52 conveys fuel to a pair of restrictions 53 and 54 in the jet system 31. The restriction 53 is fixed and the restriction 54 is normally closed by a valve 55 which is biased to closed position by a spring 56. The conduit 51 conveys fuel thru a restriction 57 in the jet system 31. All fuel passing thru the restrictions 54 and 57 must pass thru another restriction 58 before emerging from the jet system into the conduit 32.

The pressure regulator unit 33 comprises a casing 59 divided by a flexible diaphragm 60 into a pair of expandable chambers 61 and 62. The conduit 32 is connected to the chamber 62, and

a balanced valve 63 attached to the center of the diaphragm 60 controls the passage of fuel from the chamber 62 to the conduit 34. A compression spring 64 biases the valve 63 toward its closed position. A conduit 65 connects the chamber 61 to the conduit 10 and thence to the vent ring 9.

An acceleration control unit is generally indicated at 66. This unit includes a casing 67 which is divided by a rigid partition 68 and a pair of flexible diaphragms 69 and 70 into four expandable chambers 71, 72, 73 and 74. The rigid partition 68 lies between and parallel to the diaphragms 69 and 70. The diaphragms 69 and 70 are connected by a rigid force transmitting member 75, which is biased upwardly by a compression spring 76. The chamber 74 is connected thru a conduit 77 with the conduit 29, so that the chamber 74 receives fuel at the pressure existing downstream from the fuel regulator 28. The chamber 73 is connected thru a conduit 78 and conduits 65 and 10 to the vent ring 9, so that the chamber 73 is supplied with air at impact pressure. The chamber 72 is connected thru a conduit 79 to a point in the air passage 2 downstream from the throttle 5.

The chamber 71 is connected to the conduit 42 thru a cylindrical chamber 80. The valve 43 is supported by a piston 81, which may be formed integrally with valve 43, as illustrated, and which moves within the cylinder 80. A compression spring 82, located in the cylinder 80, biases the piston 81 to the position shown in the drawing, wherein the valve 43 is separated from its seat 83.

The piston 81 is bored at its center to provide a passage 84. Another passage 85 is bored thru the valve 43 in alignment with the passage 84. The passage 85 is of smaller diameter than passage 84. A laterally extending passage 86 is bored thru the side of valve member 43, and intersects the passages 84 and 85. The lower end of cylinder 80 is closed by a fixed plug 87. The plug 87 is provided with a conical projection 88 in the center of its upper surface, in alignment with passage 84 in piston 81. A narrow passage 89 is bored thru the plug 87 to the apex of the conical projection 88. A plurality of larger parallel passages 90 are bored thru the plug 87. The arrangement is such that when the piston 81 is in the position shown, any fuel flowing into the chamber 71 must pass thru the narrow passage 89. On the other hand, when the piston 81 is lifted from the position shown, as occurs during the discharge of fluid from the chamber 71, the fluid being discharged can flow thru the parallel passages 89 and 90. Hence the fluid in chamber 71 can be discharged faster than the chamber can be filled.

Operation

60 The operation of the carburetor shown will first be considered under conditions of constant throttle position, so that the acceleration control unit 66 is not operating. Under these conditions, the pressure differential established between the inlet 3 and the throat of venturi 4 is communicated to the chambers 11 and 13 of metering unit 19. This pressure differential acts upwardly on the member 24, and therefore tends to move the diaphragm 22 in a direction to close the port 25. This upward force is opposed by the pressure of the fuel in the chamber 23. As the member 24 moves upwardly, the port 25 becomes more restricted, and the pressure in chamber 23 increases. As the movement of member 24 continues, a point is reached where the downward

force due to the pressure in chamber 23 balances that due to the pressure differential between the chambers 11 and 13, and the member 24 remains in that position. It may therefore be seen that a pressure is established in chamber 23 which is a measure of the mass of air flowing thru the passage 2. This pressure in chamber 23 is communicated back thru conduit 46, check valve 45, conduit 44, past valve 43 and thru conduit 42 to chamber 37 of the fuel regulator 28.

The pressure in chamber 37 acts on the valve 39 in an opening direction, being aided by the spring 40 and opposed by the pressure in chamber 38. As the valve 39 is moved by a change in the pressure in chamber 37, the pressure in chamber 38 is varied in a sense to oppose the pressure change in chamber 37. Therefore as the movement of valve 39 continues, a position is reached at which the pressures in chambers 37 and 38 balance each other and the force of spring 40, and the valve 39 remains in that position. It may therefore be seen that the fuel flow thru the valve 39 is regulated in accordance with the pressure in chamber 37, which is in turn controlled by the mass of air flowing thru the passage 2.

The mixture control unit 30 is provided to permit the operator of the aircraft in which the carburetor is installed, to select either a rich or lean mixture, depending upon the conditions under which the aircraft is operated. The mixture control unit also may be used by the operator to completely cut off the supply of fuel to the carburetor when it is desired to stop the engine.

The jet system 31 provides a fixed restriction in the fuel line. In accordance with well-known hydraulic laws, the flow thru such a fixed restriction is a function of the pressure differential across it. The pressure regulator 33, as described in more detail below, operates to maintain a substantially constant outlet pressure on the jet system 31. Therefore the fuel flow thru the jet system, and hence the flow to the carburetor is controlled by the fuel regulator unit 28, which establishes the fuel pressure on the inlet side of the jet system 31 as a function of the air flow thru the passage 2.

The valve 55 operates to automatically enrich the mixture supplied to the engine under conditions of relatively heavy load. Such heavy load conditions are accompanied by high rates of air flow thru the passage 2, which in turn cause a high pressure differential across the jet system 31. When this pressure differential exceeds a value determined by the strength of spring 56, the valve 55 opens, thereby increasing the quantity of fuel flowing in proportion to the quantity of air.

In the pressure regulator unit 33, the pressure in chamber 62 is balanced against the pressure in chamber 61 and the force of spring 64. The pressure in chamber 61 is relatively low compared to that in chamber 62 and to the force of spring 64. Therefore the variations of pressure in 61 have relatively little regulating effect on the position of valve 63, and the unit operates to maintain a substantially constant pressure in chamber 62. Since the valve 63 is balanced against the pressure at its outlet, the variations in pressure adjacent the discharge nozzle 6 are prevented from affecting the quantity of fuel supplied to the engine. The connection of chamber 61 through conduit 65 to vent ring 9 is chiefly for the purpose of venting the chamber 61 so as to permit ready movement of the valve 63. It will

be apparent, however, that changes in atmospheric pressure do affect the operation of valve 63 to some extent. An increase in atmospheric pressure, for example, increases the pressure in chamber 61, thereby decreasing the fuel flow thru the jet system 31. Likewise, a decrease in atmospheric pressure causes an increased fuel flow. This effect may be taken into account in designing the altitude compensating valve 17.

Considering the operation of the acceleration control unit 66, it may be seen that the chamber 11 is normally filled with fuel received thru the passage 84. Under part throttle conditions the pressure in chamber 72 is considerably below atmospheric, and tends to maintain diaphragm 69 near the bottom of chamber 72. Upon an opening movement of the throttle 5, the pressure in the chamber 72 is suddenly increased, and acts upwardly on the diaphragm 69, thereby forcing the piston 81 upwardly and moving valve 43 into engagement with its seat 83, and discharging the fuel in the chamber 71 thru the passages 89, 90 and 84. Some of this fuel flows on thru passage 85 and the remainder flows thru passage 86 and the conduit 42 into the chamber 37 of fuel regulator unit 28. This increases the pressure in the chamber 37 and causes an opening movement of the valve 39 so as to increase the supply of fuel to the engine, and to provide a balancing increase of pressure in chamber 38. The increase of pressure in chamber 38 is communicated thru conduit 77 to chamber 74, thereby applying a cumulative force on the diaphragm 69 acting in a direction to more rapidly empty the chamber 71 and to further increase the pressure in chamber 37.

As soon as valve 43 engages its seat 83, the metering unit 19 no longer controls the pressure in chamber 37, but the latter pressure is controlled by the acceleration control unit 66 alone. This control continues until the chamber 71 is completely empty, whereupon the fuel in chamber 37 starts flowing thru the passages 86 and 85 to conduit 44 and metering unit 19 is again restored to control. As long as the pressure in chamber 37 is controlled by the acceleration control unit 66, the supply of fuel to the engine is increased beyond its normal proportion, thereby causing more rapid acceleration to the speed called for by the new throttle position. This increased fuel supply is sometimes called a "boosting" action.

When the throttle 5 is moved toward its closed position, the pressure on the downstream side of it decreases, thereby causing a downward movement of diaphragm 69. The pressure under piston 81 is thereby reduced, and it is again moved to the position shown in the drawing. The chamber 71 then slowly fills with fuel thru the passages 85 and 86 in parallel, and 84 and 89. This decreases the pressure in chamber 37, which causes diaphragm 36 to operate valve 39 to decrease the pressure in chamber 38. The decreased pressure in chamber 38 is communicated thru conduit 77 to chamber 74, whereupon the diaphragm 69 is given a further downward impulse. As in the case of the upward movement of diaphragm 69, the action is cumulative until the chamber 71 is completely filled.

The decreased pressure in the chamber 38 causes a decreased fuel flow to the engine. This decreased fuel flow is sometimes termed a "robbing" action. If properly proportioned, the "robbing" action aids in securing rapid deceleration of the engine corresponding to the closing movement of the throttle. If the "robbing" action is

too small or too great, the engine will not decelerate rapidly enough, or will decelerate too much.

During the accelerating phase of operation of the control unit 66, the difference between the cross-sectional areas of the passages 86 and 85 determines the amount of the increased fuel supply, since that part of the fuel discharged from chamber 71 thru the passage 85 has no effect on the quantity of fuel supplied to the carburetor. Hence, as the size of passage 85 is increased with respect to that of passage 86, the amount of the increased fuel supply to the engine is reduced.

During the decelerating phase of operation of the control unit 66, the magnitude of the decrease in the fuel supply is determined by the sum of the cross-sectional areas of the passages 85 and 86, since fuel flows thru both in parallel. Hence, by increasing the size of passage 85, the "robbing" action is increased. Similarly, a decrease in the size of passage 85 decreases the "robbing" action.

The duration of the "boosting" action and the duration of the "robbing" action are both affected similarly by a change in the size of any of the passages 84, 85 and 86. The relative duration of the "boosting" and "robbing" actions are determined by the relative sizes of the passages 89 and 90.

The check valve 45 is provided to prevent the suction in chamber 71 during the filling operation from being communicated to the chamber 23 so as to turn the diaphragm 22 inside out. If the check valve 45 were not provided, the operation of diaphragm 22 in that manner might cause it to wear out quickly.

The chambers 71 and 74, whose internal pressures act in opposite directions on the member 75, are respectively connected to chambers 37 and 38 of the fuel regulator 28. Any pressure change in chamber 37 is accompanied by a parallel change in chamber 38. Therefore, it may be seen that the operation of member 75 is not affected by variations in the pressure of the fuel source, or by any variation in pressure in chambers 37 and 38.

Also, since the chamber 73 is connected thru conduits 78 and 10 to vent ring 9, it is subject to changes in atmospheric pressure. Such atmospheric pressure changes are also effective to vary the pressure in chamber 72, where they act in a direction opposite the effect produced in chamber 73. Therefore the action of acceleration control unit 66 is balanced against the effects of variations in atmospheric pressure.

While I have shown and described the preferred embodiment of my invention, other modifications thereof will occur to those skilled in the art, and I therefore intend that my invention shall be limited only by the appended claims.

I claim as my invention:

1. In a carburetor for an internal combustion engine, in combination, a source of fuel under superatmospheric pressure, a conduit for conveying fuel to said engine, valve means actuated solely by variations of fuel pressure for controlling the flow of fuel thru said conduit, throttle means for controlling the flow of air thru said carburetor, means responsive to the air pressure at a point downstream from said throttle means and hydraulically connected to said valve means for varying the fuel pressure applied to said valve means and effective upon an increase in said air pressure to vary said fuel pressure in a sense to increase the flow of fuel thru said valve means, and means for counterbalancing the effect of

variations in atmospheric pressure on said air pressure responsive means.

2. In a carburetor for an internal combustion engine, in combination, a source of fuel under superatmospheric pressure, a conduit for conveying fuel to said engine, valve means actuated solely by variations of fuel pressure for controlling the flow of fuel thru said conduit, throttle means for controlling the flow of air thru said carburetor, means responsive to the air pressure at a point downstream from said throttle means and hydraulically connected to said valve means for varying the fuel pressure applied to said valve means and effective upon an increase in said air pressure to vary said fuel pressure in a sense to increase the flow of fuel thru said valve means, means for counterbalancing the effect of variations in said fuel pressure on said valve means, and means for counterbalancing the effect of variations in atmospheric pressure on said air pressure responsive means.

3. In a carburetor for an internal combustion engine, in combination, a source of fuel under superatmospheric pressure, a conduit for conveying fuel to said engine, valve means actuated solely by variations of fuel pressure for controlling the flow of fuel thru said conduit, throttle means for controlling the flow of air thru said carburetor, means responsive to the air pressure at a point downstream from said throttle means and hydraulically connected to said valve means for varying the fuel pressure applied to said valve means and effective upon an increase in said air pressure to vary said fuel pressure in a sense to increase the flow of fuel thru said valve means, and means for counterbalancing the effect of variations in said fuel pressure on said air pressure responsive means.

4. A fuel supply system for an internal combustion engine, comprising in combination, a source of fluid fuel, a first conduit for conveying fuel from said source to said engine, a metering restriction in said conduit, valve means actuated solely by variations of fuel pressure for controlling the fuel flow thru said conduit, passage means for conveying air for combustion purposes to said engine, means responsive to the quantity of air flowing thru said passage means separate from and normally connected only hydraulically to said valve means to control the operation of said valve means and thereby control said fuel flow in proportion to said air flow, throttle means for controlling the flow of air thru said passage means, and means responsive to the air pressure in said passage means at a point downstream from said throttle means, hydraulically connected to said valve means and said air quantity responsive means, and effective upon an increase in said air pressure to remove said air quantity responsive means from control of said valve means and to operate said valve means to increase the fuel flow therethru.

5. In a carburetor, in combination, throttle means for controlling the flow of air thru said carburetor, valve means actuated solely by variations of fuel pressure for controlling the flow of fuel thru said carburetor, means responsive to the air pressure at a point downstream from said throttle means, hydraulically connected to said valve means, and effective upon an increase in said air pressure to operate said valve means to increase the flow of fuel therethru, and means responsive to the flow of fuel thru said valve means to cumulatively increase said fuel flow.

6. In a carburetor for an internal combustion

engine, in combination, a conduit, means for supplying fuel under pressure through said conduit to said engine, valve means actuated solely by variations in fuel pressure for controlling said fuel supply to said engine, an expansible chamber having a movable wall, passage means connecting said conduit and said chamber, means for balancing said wall against the effect of variations in pressure within said chamber, throttle means for controlling the flow of air thru said carburetor, and means operative as an incident to a movement of said throttle to apply an unbalanced force to said wall and thereby initiate movement thereof, said balancing means having means effective upon initiation of movement of said wall by said force applying means to counterbalance the change of pressure in said chamber caused by the movement of said wall and thereby to cause continuous movement of said wall as long as said force is applied until the wall reaches the limit of its range of movement.

7. In a fuel supply system for an internal combustion engine, in combination, a first conduit for conveying air to said engine for combustion purposes, a second conduit for conveying fuel to said engine, a source for supplying fuel to said second conduit under superatmospheric pressure, means associated with said first conduit for producing two unequal pressures whose difference is a measure of the quantity of air flowing therethru, a metering restriction in said second conduit, means for controlling the pressure differential across said restriction to control the flow of fuel therethru, a third conduit supplied with fuel from said source and including a restriction, an expansible chamber connected to said third conduit and having a movable wall operatively connected to said pressure differential controlling means for positioning the same, valve means for controlling the flow of fluid thru said third conduit and thereby the pressure in said chamber and the position of said pressure differential controlling means, means subjected to said two unequal pressures for operating said valve means in accordance with the difference of said pressures, and means responsive to an increase in air pressure in said first conduit for additionally controlling the pressure in said chamber to move said pressure differential controlling means in a fuel flow increasing direction.

8. In a fuel supply system for an internal combustion engine, a liquid fuel conduit, a metering restriction in said conduit, a main valve for regulating the pressure in said conduit on one side of said restriction, an expansible chamber having a movable wall subject on its external surface to the regulated fuel pressure in said conduit on said one side of said restriction, a restricted inlet passage connecting said chamber to said conduit, a restricted outlet passage connecting said chamber to a point maintained at a lower pressure, a connection between said wall and said valve for moving said valve in an opening direction when the pressure in said chamber increases, pilot valve means for controlling one of said restricted passages, means responsive to the rate of flow of combustion air to said engine for operating said pilot valve means, a throttle for controlling the flow of air to said engine, a pump operative to discharge fuel upon an opening movement of said throttle, an inlet conduit for supplying fuel to said pump, a discharge conduit for conveying fuel from said pump to said chamber, and a fixed restriction in said pump discharge conduit for retarding the increase in pressure in said chamber.

and the consequent opening movement of said valve in response to operation of said pump, the fixed restriction in said pump discharge conduit delaying restoration of said valve to its normal operating condition following an operation of said pump.

9. A fuel supply system for an internal combustion engine, comprising in combination, means for supplying fluid fuel under superatmospheric pressure, a first conduit for conveying fuel from said fuel supply means to said engine, a metering restriction in said conduit, first valve means for controlling the fuel flow thru said conduit, a first expansible chamber having a movable wall operatively connected to said first valve means for positioning the same, a restricted inlet passage connecting said fuel conduit and said first chamber, a restricted outlet passage for said chamber, second valve means in said outlet passage, passage means for conveying air for combustion purposes to said engine, means responsive to the quantity of air flowing thru said passage means to operate said second valve means and thereby to control said fuel flow in proportion to said air flow, throttle means for controlling the flow of air thru said passage means, a second expansible chamber, a restricted passage connecting said first and second chambers, means responsive to the air pressure in said passage means at a point downstream from said throttle means and effective upon an increase in said air pressure to contract said second chamber and thereby supply additional fuel to said first chamber so as to operate said first valve means to increase the fuel flow therethru, and valve means operated as an incident to the discharge of fluid from said second chamber to close said restricted outlet passage between said first chamber and said second valve means.
10. A fuel supply system as in claim 9 including flexible diaphragm means forming a part of said operating means for said second valve means, and a check valve in said outlet passage between said first chamber and said second valve means.
11. A fuel supply system as in claim 9 including means for counterbalancing the effect of variations in the fuel pressure downstream from said first valve means on the expansion of said second chamber.
12. A fuel supply system as in claim 9 including means for counterbalancing the effect of variations in atmospheric pressure on the expansion of said second chamber.
13. A fuel supply system as in claim 9 including means for counterbalancing the effect of variations in the fuel pressure downstream from said first valve means on the expansion of said second chamber, and means for counterbalancing the effect of variations in atmospheric pressure on the expansion of said second chamber.
14. A fuel supply system for an internal combustion engine, comprising in combination, means for supplying fluid fuel under superatmospheric pressure, a first conduit for conveying fuel from said fuel supply means to said engine, a metering restriction in said conduit, first valve means for controlling the fuel flow thru said conduit, a first expansible chamber having a movable wall operatively connected to said first valve means for positioning the same, a restricted inlet passage connecting said fuel conduit and said first chamber,

11

ber, a restricted outlet passage for said chamber, second valve means in said outlet passage, passage means for conveying air for combustion purposes to said engine, means responsive to the quantity of air flowing thru said passage means to operate said second valve means and thereby to control said fuel flow in proportion to said air flow, throttle means for controlling the flow of air thru said passage means, and an acceleration control unit comprising a casing, a pair of flexible diaphragms extending laterally of said casing, a rigid wall extending laterally of said casing between said diaphragms, said diaphragms and said wall dividing said casing into four expandable chambers, a rod connecting said diaphragms and extending thru said wall, restricted passage means connecting one of said four chambers to said restricted outlet passage, check valve means operative upon contraction of said one of said four chambers to close said restricted outlet passage between said first chamber and said second valve means so that the pressure in said first chamber is then controlled by the pressure in said one chamber and not by said second valve means, means connecting a second of said four chambers to said air passage means at a point downstream from said throttle means, means for venting a third of said four chambers to atmosphere so as to balance said diaphragms against variations in atmospheric pressure, and means connecting the fourth of said four chambers to said first conduit between said first valve means and said metering restriction so as to balance said diaphragms against variations in the fuel pressure there existing.

15. A fuel supply system as in claim 9 including means responsive to the pressure in said first conduit between said first valve means and said metering restriction for controlling the rate of contraction of said second chamber cumulatively with said air pressure responsive means.

16. A fuel supply system for an internal combustion engine, comprising a first conduit for conveying combustion air to said engine, means associated with said conduit for producing two unequal air pressures whose difference is a measure of the rate of flow of air thru said conduit, means for supplying fuel under superatmospheric pressure, a second conduit for conveying fuel from said fuel supply means to said engine, a metering restriction in said second conduit effective to control the flow of fuel therethru as a function of the fuel pressure differential thereacross, a main valve for variably restricting said second conduit to control the pressure in the portion of said conduit between said valve and said restriction, an expandible chamber having a movable wall subject on its exterior surface to the fuel pressure in said portion of said second conduit, said wall being operatively connected to said main valve for positioning the same, a restricted inlet passage connecting the interior of said chamber to said second conduit, a restricted outlet passage connecting the interior of said chamber to a point maintained at a continuously lower pressure, second valve means for controlling said restricted outlet passage, means responsive to the difference of said air pressures for operating said second valve means, throttle means for controlling the flow of air thru said first conduit, and means operative as an incident to an opening movement of said throttle means to vary the pressure in said chamber in a sense to cause an opening movement of said main valve and thereby to increase the fuel flow therethru.

12

17. A fuel supply system for an internal combustion engine, comprising a first conduit for conveying combustion air to said engine, means associated with said conduit for producing two unequal air pressures whose difference is a measure of the rate of flow of air thru said conduit, means for supplying fuel under superatmospheric pressure, a second conduit for conveying fuel from said fuel supply means to said engine, a metering restriction in said second conduit effective to control the flow of fuel therethru as a function of the fuel pressure differential thereacross, a main valve for variably restricting said second conduit to control the pressure in the portion of said conduit between said valve and said restriction, an expandible chamber having a movable wall subject on its exterior surface to the fuel pressure in said portion of said second conduit, said wall being operatively connected to said main valve for positioning the same, a restricted inlet passage connecting the interior of said chamber to said second conduit, a restricted outlet passage connecting the interior of said chamber to a point maintained at a continuously lower pressure, second valve means for controlling said restricted outlet passage, means responsive to the difference of said air pressures for operating said second valve means, throttle means for controlling the flow of air thru said first conduit, and means operative as an incident to an opening movement of said throttle means, to close said outlet passage and to supply additional fuel to said chamber so as to operate said main valve to increase the fuel flow therethru.

35. 18. In a carburetor for an internal combustion engine, in combination, a source of fuel under superatmospheric pressure, a conduit for conveying fuel to said engine, valve means actuated solely by variations in fuel pressure for controlling the flow of fuel through said conduit comprising a valve member, an expandible chamber having a movable wall, a connection between said wall and said valve member, a restricted fluid inlet passage to said chamber, a restricted fluid outlet passage from said chamber, means for varying the effective area of said outlet passage to control the pressure in said chamber and thus the movements of said valve member, and pump means for supplying additional fluid to said chamber to control the pressure therein and the movements of said valve member independently of the area varying means.

SCOTT F. HUNT.
